Melvin A. Menk, Englewood, and Verlos G. Sharpe, Xenia, Ohio, assignors to General Motors Corporation, Detroit, Mich., a corporation of Delaware

Filed Feb. 11, 1969, Ser. No. 15,740

Term of patent 14 years

Int. Cl. D15—06

U.S. Cl. D49—1

FIGURE 1 is a front elevational view of a combined washer-dryer laundry appliance embodying our new design;

FIGURE 2 is a side elevational view of the right side as taken along the line 2—2 of FIGURE 1;

FIGURE 3 is a top plan view as taken along line 3—3 of FIGURE 1;

FIGURE 4 is a rear elevational view as taken along line 4—4 of FIGURE 2; and

FIGURE 5 is a left front perspective view thereof.

It is to be understood that the left side thereof is similar but opposite to FIGURE 2.

We claim:

The ornamental design for a housing for a combination washer-dryer laundry appliance, as shown and described.
